CUP FOR AN ACOUSTICAL COUPLER

John P. Kennedy, 2198 Woodstock Road,
Columbus, Ohio 43221

Filed Sept. 9, 1971, Ser. No. 179,253

Term of patent 14 years

Int. Cl. D14—03

U.S. Cl. D26—14 A

FIG. 2

FIG. 1

FIG. 3

FIG. 4

FIG. 5

FIG. 1 is an overall view in perspective of the cup for an acoustical coupler showing my new design;

FIG. 2 is a top plan view of the cup of FIG. 1;

FIG. 3 is a first side view of the cup of FIG. 1;

FIG. 4 is a second side view of the cup of FIG. 1;

FIG. 5 is a side elevation of the cup element in its working environment.

The broken lines are shown for illustrative purposes only.

I claim:

The ornamental design for a cup for an acoustical coupler, as shown and described.
